WALL BRACKET FOR A TELEVISION SET

Arnold R. Dahlberg, Minneapolis, Minn., assignor to
The Dahlberg Company, a corporation of Minnesota

Application June 4, 1959, Serial No. 56,218

Term of patent 14 years

(Cl. D33—3)

Fig. 1 is a perspective view of a wall bracket for a television set, showing my new design with a television receiver being shown in broken lines for illustrative purpose only;

Fig. 2 is a side elevation view;

Fig. 3 is a front elevational view;

Fig. 4 is a top plan view; and

Fig. 5 is a bottom plan view thereof.

I claim:

The ornamental design for a wall bracket for a television set, as shown and described.
